MIRROR FRAME FOR TRUCKS OR THE LIKE

Kenneth J. Fischer, 3248 Fruitwood Lane,
Jacksonville, Fla. 32202

Filed Feb. 24, 1971, Ser. No. 118,589

Term of patent 14 years

Int. CL. D12—16

U.S. CL. D14—6

FIG. 1

FIG. 2

FIG. 3

FIG. 4

FIG. 1 is a front perspective view of the mirror frame for trucks showing my new design;

FIG. 2 is a top plan view of FIG. 1;

FIG. 3 is a rear elevational view of FIG. 1; and

FIG. 4 is a cross-sectional view on an enlarged scale taken along line 4—4 of FIG. 2.

I claim:

The ornamental design for a mirror frame for trucks or the like, substantially as shown.
